CHAIR CONSTRUCTION

Thomas A. Friedlander, Baltimore, Md.

Application October 22, 1948, Serial No. 55,999

4 Claims. (Cl. 155—196)

1

The present invention relates to a novel chair construction. More particularly, the present invention relates to a chair including a novel frame therefor.

Upholstered chairs as now produced include a frame portion functioning as a support for the cushions and other upholstered sections of the chair. This frame portion is generally integral with the legs, and it has been customary in manufacturing chairs of this type to have the rear legs extending generally downward in the same plane as the back. When the back of the chair is upholstered, therefore, it will extend outwardly beyond the rear legs of the chair and if the chair is pushed toward a wall, the back will tend to strike the wall resulting in wear on the chair and, in some instances, discoloration or abrasion of the wall.

It is one of the objects of the present invention, therefore, to provide a novel chair wherein the rear legs extend rearwardly from the back thereof so that when the chair is placed in proximity to a wall the legs of the chair will strike the baseboard or lower portion of the wall and prevent contact of the back of the chair therewith.

A second general object of the present invention is to provide a novel frame construction including the rear legs of a chair wherein the rear legs extend rearwardly a substantial distance.

A third general object of the present invention is to provide a novel chair construction including a frame, a portion of the frame being constituted by rear leg members which are firmly held in position and joined to the remaining portions of the frame structure.

A fourth object of the present invention is to provide a chair construction, and particularly a frame therefor, including a novel connecting joint between a protruding rear leg and the horizontal frame members which will resist the turning moment produced by protrusion of the rear legs and firmly maintain said rear legs in assembled position with the remainder of the frame.

Other objects and the nature and advantages of the instant invention will be apparent from the following description taken in conjunction with the accompanying drawings, wherein:

Figure 1 is a side elevation of a frame member in accordance with the present invention;

Figure 2 is a front elevation of the frame member of Fig. 1;

Figure 3 is a plan view of the frame member of Fig. 1;

2

Figure 4 is a detail perspective of the construction of the frame member;

Figure 5 is a further detail perspective illustrating the joints between the rear leg and the remainder of the frame;

Figure 6 is an exploded perspective view of the legs and connecting members;

Figure 7 is a perspective view of the front leg of Fig. 6 taken from the reverse side thereof;

Figure 8 is a plan view of a portion of a modified joint construction;

Figure 9 is an exploded view of the rear and front leg of the modified construction;

Figure 10 is a side elevation of the modification corresponding to Fig. 8; and

Figure 11 is a fragmentary view illustrating another modified form of the invention.

Referring to the figures of the drawings and particularly Fig. 1 thereof, a chair frame is indicated in general at 10. This chair frame is adapted to be covered with a suitable upholstery so as to form the chair corresponding in shape to the dotted lines indicated at 11. As shown, the chair frame includes four leg members including the rear leg members 12 and 13 and the front leg members 14 and 15. The rear leg members are of generally curved conformation and extend outwardly so that the lower rearward portion of the rear leg members extend substantially beyond the upper portion thereof, even when the upper portion is covered with upholstery. Thus, when the chair is positioned against a wall indicated at W, Fig. 1, the contact with the wall and/or the baseboard thereof will take place at the point indicated at 16 and it will be impossible for the upper end of the chair to touch the wall.

This extension of the lower rear leg of the chair beyond the vertical plane of the back or upper end of the leg member will produce a relatively great amount of twist or turning moment at the point of connection between the rear legs and the horizontal frame members, as will be hereafter pointed out in detail. The rear leg member 12 is connected to the rear leg member 13 by a pair of horizontal structural members 17 and 18. The rear leg member 12 is connected to the front leg member 14 by a pair of horizontal structural members 19 and 20. The rear leg member 13 is connected to the front leg member 15 by a pair of horizontal members 21 and 22.

As best shown in Fig. 6, the horizontal members 21 and 22 are joined to the rear leg 13 and the front leg 15 by a joint construction especially desirable for resisting the turning moment of the

rear leg 13 at the point of connection between the rear leg and the horizontal members. The joint includes a T-shaped male member indicated at 23 and extending from a pair of shoulders 23a and 23b at the end of the horizontal structural member 21 which is adapted to fit into a T-shaped female joint portion 24 in the leg 13; the male portion 23 and shoulders 23a and 23b forming a generally H-shaped male portion having a part thereof fitting into the T-shaped female portion 24 and the shoulders 23a and 23b fitted against the inside edge 13a of the leg 13. Preferably the female portion 24 is not cut completely through the leg so as to enable an easy assembly of the leg 13 with the horizontal structural member 21. By utilizing this type of joint any twist or turning moment will be resisted by the horizontal portions of the T, as, for example, the surface 25 and also by the remainder of the joint construction. A similar type of joint connects the leg 13 to the horizontal structural members 17 and 18, the member 17 being provided with a similar T-shaped end 26 extending from a pair of shoulders 26a and 26b which fits into a T-shaped cut 27 in the rear leg 13.

As shown in Fig. 6, the rear leg 13 is preferably formed from a pair of pieces indicated at 28 and 29. As may be understood, by forming the rear leg from a pair of pieces it is very much easier to produce the T-shaped female portions of the joint.

The front leg 15 is provided with a pair of T-shaped female joint portions toward its lower end, these female joint portions being indicated at 30 and 31. The portion 30 is adapted to receive the male portion 32 on the end of the horizontal frame member 21. The portion 31 is adapted to receive a similar T-shaped portion 33, as best shown in Fig. 2, on the horizontal connection member 34. Similarly the member 22 is provided with a pair of T-shaped male members 35 and 36 which are received respectively within the female portions 37 and 38 on the rear leg 13 and the front leg 15 respectively.

The rear and front legs are also held together by a suitable arm rest 39 which is suitably fastened at its front and rear ends to the legs. As may be understood, the various frame members are assembled and held together with a suitable glue supplemented by nails or screws or other fastening means.

In the modification of Figs. 8 to 10 inclusive, a modified form of construction is illustrated. The horizontal structural members, indicated at 40 and 41 respectively, are each provided with reduced ends 42 and 43 respectively, adapted to fit into slotted or cut portions 44, 45 and 46, at the lower end of the rear leg 12, for example, as best shown in Figs. 8 and 10. The corresponding front leg 14 is also provided with slotted or cut portions 47, 48 and 49 which are adapted to similarly receive reduced ends of the horizontal frame structure which is otherwise entirely similar to that described in connection with the previous modification. There is also provided in this modification of the device a corner reinforcing member 50 which is fastened to the horizontal structural members 41 and 40 as by the screws 51 and 52. In this modification of the device it is to be noted that the reduced ends 42 and 43 are fitted into the rear leg 12 for assembly in such a manner that a plurality of horizontal contacting surfaces are provided to take the turning moment of the rear leg.

Referring to Figure 11 there is shown a portion

of a rear leg 12 illustrating a modified form of joint. In this form of the invention, the horizontal structural member 19 is provided with a keystone shaped end 53 so as to provide a pair of edges 54 and 55 capable of fulfilling the function of the T male member previously described, and angularly disposed relative to the vertical bearing surfaces 56 at the end of the keystone and the vertical shoulders 57 and 58. In other words, the edges 54 and 55, together with the other bearing surfaces, are capable of resisting the turning moment between the rear leg 12 and the horizontal structural member 19. As may be understood, the remaining joints may be similarly provided with a keystone shaped male member fitting into a suitable female member in the leg 12 or in the other legs of the chair.

Although in the present description of the invention the article of furniture incorporating the present improvements has been described and shown as a chair, it is within the more general scope of the present invention to utilize a chair of any width and to embody the present invention within other similar articles of furniture, such as those known as sofas, and where in the present description and claims the term "chair" is used, such other articles of furniture are thereby included.

It will be obvious to those skilled in the art that various changes may be made without departing from the spirit of the invention and therefore the invention is not limited to what is shown in the drawings and described in the specification but only as indicated in the appended claims.

I claim:

1. In a chair construction, a frame for use as a base for upholstery, comprising a pair of front legs and a pair of rear legs, horizontal structural members connecting said front and rear legs, each of said rear legs having an upper portion forming a back and a lower portion forming the support for said frame, said rear legs having a gradually increasing taper extending from said upper portion toward said lower portion, the rear portion of said rear legs including said upper and lower portions having a curved configuration, said curved lower portion extending rearwardly beyond said curved upper portion so as to prevent contact of said back with a generally vertical surface when said chair is positioned adjacent thereto, and joint means including interlocking portions having coacting vertical bearing surfaces and angularly disposed surfaces resisting a turning moment and connecting said rear legs and said horizontal structural members at the thickest section of said rear legs, thereby providing greater rigidity for said frame.

2. In a chair construction, a frame for use as a base for upholstery, comprising a pair of front legs and a pair of rear legs, horizontal structural members connecting said front and rear legs, each of said rear legs having an upper portion forming a back and a lower portion forming the support for said frame, said rear legs having a gradually increasing taper extending from said upper portion toward said lower portion, the rear portion of said rear legs including said upper and lower portions having a curved configuration, said curved lower portion extending rearwardly beyond said curved upper portion so as to prevent contact of said back with a generally vertical surface when said chair is positioned adjacent thereto, and joint means connecting said rear legs and said horizontal struc-

tural members at the thickest section of said rear legs, thereby providing greater rigidity for said frame, said joint means including vertical and angular surfaces.

3. In a chair construction, a frame for use as a base for upholstery, comprising a pair of front legs and a pair of tapered rear legs, horizontal structural members connecting said front and tapered rear legs, each of said tapered rear legs having an upper portion forming a back and a lower portion forming the support for said frame, the rear portion of said tapered rear legs including said upper and lower portions having a curved configuration, said curved lower portion extending rearwardly beyond said curved upper portion so as to prevent contact of said back with a generally vertical surface when said chair is positioned adjacent thereto, and joint means connecting said tapered rear legs and said horizontal structural members, said joint means including interlocking portions having coacting vertical bearing surfaces and angularly disposed surfaces resisting a turning moment, said interlocking portions being located at the thickest portion of said legs, thereby providing greater rigidity for said frame.

4. In a chair construction, a frame for use as a base for upholstery, comprising a pair of front legs and a pair of tapered rear legs, horizontal structural members connecting said front and rear legs, each of said tapered rear legs having an upper portion forming a back and a lower portion forming the support for said frame, the

10 rear portion of said tapered rear legs including said upper and lower portions having a curved configuration, said curved lower portion extending rearwardly beyond said curved upper portion so as to prevent contact of said back with a generally vertical surface when said chair is positioned adjacent thereto, and joint means interlocking said tapered rear legs and said horizontal structural members at the thickest portion of said rear legs, thereby providing greater rigidity for said frame.
